(57) **CLAIM**

The ornamental design for acupressure massage device, as shown and described.

DESCRIPTION

FIG. 1 is a perspective view of the massage device in a closed position;

FIG. 2 is a front view thereof;

FIG. 3 is a top plan view thereof;

FIG. 4 is a bottom plan view thereof;

FIG. 5 is a side view thereof;

FIG. 6 is a perspective view of the massage device in an opened position;

FIG. 7 is a front view thereof;

FIG. 8 is a top plan view thereof;

FIG. 9 is a bottom plan view thereof;

FIG. 10 is a right side view thereof; and,

FIG. 11 is a left side view thereof.

1 Claim, 2 Drawing Sheets
